UNITED STATES PATENT OFFICE.

PAUL L. T. HÉROULT, OF LA PRAZ, FRANCE, ASSIGNOR TO SOCIETE ELECTRO-METALLURGIQUE FRANCAISE, OF FROGES, ISÈRE, FRANCE.

ELECTRIC FURNACE.

No. 913,888.

Specification of Letters Patent.

Patented March 2, 1909.

Application filed May 3, 1907. Serial No. 371,691.

To all whom it may concern:

Be it known that I, PAUL LOUIS TOUS-SAINT HÉROULT, a citizen of the Republic of France, residing at La Praz, Savoie, France, have invented certain new and useful Improvements in Electric Furnaces, of which the following is a specification.

This invention aims to provide for the varying of the arc gap in arc furnaces, or of the degree of contact in incandescent furnaces, so as to control in either case the current passing through the furnace with the use of an electrode which is fixed, at least during operation. This fixity of the electrode serves to eliminate various difficulties encountered in previous types of furnace in which the electrode has had to be adjusted through a water-cooled stuffing-box, and in which the construction of this stuffing-box and also of the connections and supports of the outer end of the electrode were more or less complicated.

According to my present invention the face of the charge which is opposite the end of the electrode is moved toward and from the electrode, being at the same time retained in a position parallel to itself. This movement of the charge is adapted to vary the resistance and consequently the current by shortening the gap in an arc furnace or by varying the degree of contact with the electrode in an incandescent furnace. The face of the charge is preferably maintained parallel to itself by being fed on an inclination corresponding with the natural slope of the material, this slope being approximately the same for all dry substances which might be used in electric furnaces. Such a slope or inclination maintains itself always at about the same angle, depressions which occur therein during the operation of the furnace being automatically filled up.

Various other features of improvement are referred to in detail hereinafter.

The accompanying drawings illustrate embodiments of the invention.

Figure 1 is a longitudinal section approximately on the line 1—1 of Fig. 2. Fig. 2 is a horizontal section approximately on the line 2—2 of Fig. 1. Fig. 3 is a detail showing other arrangements. Fig. 4 is a detail showing the operation of an incandescent furnace.

Referring to the embodiment of the invention illustrated in Figs. 1 and 2, the furnace may have a base A of carbon constituting a

stationary terminal and from which the current is carried away in any suitable manner, and side walls B and overhanging walls C of clay or other nonconducting material. The material is fed in to the furnace by way of a shaft D of less diameter than the body of the furnace in proportion to the length of the overhanging walls C. The charge E, which may, for example, be of iron ore and coke, is in the form of a vertical or approximately vertical column which spreads out below the overhanging walls C, and maintains a slope F which is approximately 42 degrees. The overhang of the walls C is made just sufficient to provide a triangular space G which will accommodate the electrode and slide hereinafter referred to. The corner of the overhanging walls C is preferably provided with a circulating pipe H for cooling it, so as to make it durable. Into the triangular space G is extended the end of one or more electrodes J, and the end of the electrode is tapered off so as to be parallel to the slope F, or will taper itself in a short time. The electrode may pass through a bushing K, cooled or not as desired, and which may serve as a contact or a cap L, with the usual connections to the cable M, may be provided, and provision may also be made for adjusting the electrode, as by means of the screw N indicated in Fig. 1.

The movement of the charge is effected by means of a slide O which is adapted to be withdrawn under the edge of the overhanging wall C, as shown in full lines, or to be projected sufficiently to move the slope F back to the dotted line F'. This slide, for example, may be a flat plate (water cooled, if necessary) of a sufficient breadth to cover the electrode and protect it from the charge at the sides, and may be provided with a screw P at the outer end for manipulating it. A bushing Q may be provided where it passes through the wall of the furnace. This arrangement is adapted for furnaces utilizing either a continuous or an alternating current, and for either a single pair of terminals or any multiple arrangement. For example, in Fig. 2 it is indicated as applied to a three-phase system, the generators R having one terminal connected to the electrodes respectively, and the other terminal connected to the carbon base A of the furnace. The current will pass from any one generator to the corresponding electrode,

thence through the arc and through the more or less resistant solid charge E to the liquefied portion S of the charge which collects at the bottom of the furnace, and 5 thence out by way of the carbon base. The term "arc furnace" as used here is applied to furnaces of the type shown in Figs. 1, 2 and 3 in which there is an arc employed, notwithstanding the fact that the current 10 after jumping the arc passes through the charge in the same manner as in an incandescent furnace; the term "incandescent" being applied only to the type of furnace which operates entirely on the incandescent 15 principle without the use of any definite arcs.

Instead of arranging the system with a star connection as shown, the bottom connection of the furnace may be suppressed and the electrodes arranged in a triangular 20 connection, in which case it will operate as in other well known three-phase furnaces, the current passing from one electrode to the others.

By adjusting the electrode J inwardly until it makes contact with the charge, the furnace will operate as an incandescent furnace exclusively. The depth and other dimensions of the furnace may be so designed as to adapt it for use either as an incandescent 30 cent or as an arc furnace.

For arc furnaces the end of the electrode should be faced off approximately parallel to the charge. But it is immaterial in what direction the electrode itself lies. For example, it may be arranged vertically, as shown in full lines at J' in Fig. 3, or obliquely, as shown in dotted lines at J². Likewise the means for shifting the charge toward and from the electrode may be differently 40 arranged. For example, a vertical slide O' may be used, as in Fig. 3, lying against the inner face of the shaft D and adjustable vertically and held in position as by a screw T.

For an incandescent furnace the electrode 45 J³, Fig. 4, may be arranged in such a position as to be always in contact with the charge E over a greater or less portion of the face of the electrode, thus increasing or diminishing the resistance without varying the character 50 of the furnace. The same means may be used in shifting the charge as are proposed in connection with furnaces of the arc type.

Furnaces of this type have the great advantage that they may be open at the top. 55 The escaping gases may be freely burned, and the combustion may be utilized to pre-heat the charge. For example, the shaft D may be extended upwardly sufficiently to form a chimney through which pass one or 60 more tubes U carrying the charge and emptying into the body E of the charge. Supposing the smelting of iron ore to be under consideration, the lower ends of the tubes U may be placed at approximately the 65 point where the rising carbon monoxid has

accomplished the reduction of the ore to the fullest extent possible, and has been so far converted into carbon dioxid that the mixture may be said to be saturated with the latter, so that if the gases passed any further 70 through the charge there would be a burning of the coke which would counterbalance or overbalance the reduction of the ore. At this point the escaping gases may be burned, being rich in carbon monoxid, and the heat 75 of combustion will be transmitted through the tubes U or by any other means to the charge therein, thus lessening the work of the current by an amount which would otherwise be necessary for supplying a large number 80 of heat units.

In the ordinary furnace with a vertical electrode about which the charge passes, there is at the lower corners of the electrode a forced contact with the charge, of which 85 particles of molten iron absorb portions of the electrode so as to eat away its end. By the passing of the current to the inclined face of the charge as shown, any contact of the charge with the electrode may be avoided, and this eating away of the end of the electrode may be eliminated. Again, with the ordinary vertical electrode there is formed immediately about the arc carbon monoxid, and a slight distance above the 95 arc carbon dioxid, which attacks the sides of the electrode, (especially on account of its temperature being higher than that of the adjacent charge), and burns it, so that the end of the electrode is reduced to the shape 100 of a knob connected by a smaller neck with the upper part of the electrode. But by feeding the charge on an incline as shown, the end of the electrode is in a substantially permanently closed space and is not exposed 105 to any of the gases except the carbon monoxid formed immediately about it and which is not oxidizing. These advantages are irrespective of the fixity or movability 110 of the electrode.

I do not claim in this application the process above described, the same being claimed in a divisional application No. 462,430, filed November 13, 1908.

Though I have described with great particularity of detail certain embodiments of my invention, yet it is not to be understood therefrom that the invention is restricted to the particular embodiments disclosed. Various modifications may be made by those 115 skilled in the art without departure from the invention.

What I claim is:—

1. An electric furnace including in combination a stationary terminal, an electrode, and means for shifting a face of the charge toward and from said electrode. 125
2. An electric furnace including in combination means for maintaining the charge with an inclined face, an electrode opposite 130

said inclined face, and means for shifting the inclined face of the charge toward and from said electrode.

3. An electric furnace having side walls B 5 for maintaining a column of the charge, an overhanging wall C, a shaft D above said overhanging wall and through which the charge is fed, and an electrode beneath said overhanging wall, said parts being proportioned and located to permit the removal of 10 the electrode out of contact with the charge.

4. An electric furnace having an electrode with its end in an inclosed space so as to be exposed to no gases except those formed 15 immediately about it, and having a shaft D communicating with the upper part of said inclosed space.

5. An electric furnace having an open shaft D through which the charge enters, 20 and having tubes U for conducting the charge to a point within said shaft, whereby the burning of the gases above such point

may heat the charge as it passes through the tubes U without direct contact of the gases with the charge, and having an electrode 25 entering the furnace at the side.

6. An electric furnace having an overhanging wall C, an electrode beneath said overhanging wall, and a slide adapted to engage the material passing the edge of said 30 overhanging wall and to shift the face of such material toward and from the electrode.

7. An electric furnace including in combination an electrode, and means overlying the 35 same and controlling the proximity or degree of contact of the charge with the electrode.

In witness whereof, I have hereunto signed my name in the presence of two subscribing witnesses.

PAUL L. T. HÉROULT.
